UNITED STATES PATENT OFFICE.

FERDINAND J. TILLMAN, OF ST. LOUIS, MISSOURI, ASSIGNOR TO TYPEWRITING CALCULATING ATTACHMENT COMPANY, OF ST. LOUIS, MISSOURI, A CORPORATION OF MISSOURI.

CALCULATING-MACHINE.

1,223,010.

Specification of Letters Patent. Patented Apr. 17, 1917.

Application filed May 21, 1913. Serial No. 769,032.

To all whom it may concern:

Be it known that I, FERDINAND J. TILLMAN, a citizen of the United States of America, and a resident of the city of St. Louis and State of Missouri, have invented 5 certain new and useful Improvements in Calculating-Machines, of which the following is a full, clear, and exact description, reference being had to the accompanying 10 drawings, forming a part of this specification.

My invention relates to a calculating machine intended, more particularly, to be placed in operation by the numeral key levers of an ordinary typewriting machine. One of the objects of the present invention is to provide a simple and efficient automatic locking mechanism for the calculating machine transmission shaft. Another 20 object is to provide the integer wheels of the machine with yielding teeth that initially engage the wheels coöperable with the integer wheels, whereby interference or clash between the coöperating teeth is avoided. The present invention also has for 25 its object the improvement of several details of construction in a machine of the kind herein referred to, as will be herein-after pointed out.

30 Figure I is a top or plan view of my machine.

Fig. II is a vertical longitudinal section taken on line II—II, Fig. I.

Fig. III is a vertical longitudinal section 35 taken through the rear portion of the machine on line III—III, Fig. I.

Fig. IV is an enlarged view partly in elevation and partly in vertical section of one of the presser levers and the adjustable 40 member carried thereby which receives engagement of the key levers.

Fig. V is an enlarged perspective view of one of the dogs by which movement of the integer wheels is controlled.

45 Fig. VI is an enlarged perspective view of one of the detents associated with the dogs which control the integer wheels.

Fig. VII is a perspective view of one of the integer wheels and the cam lever for 50 imparting initial movement to said wheel.

Fig. VIII is an enlarged section of a portion of one of the integer wheels, showing in detail one of its yielding teeth.

Fig. IX is a section taken on line 5 IX—IX, Fig. X.

Fig. X is a top or plan view of the locking mechanism controlling operation of the transmission mechanism.

Fig. XI is an enlarged view partly in elevation and partly in section on line XI—XI, 60 Fig. X, of the lower end of the release arm of the transmission shaft locking mechanism and the detent operating means engaged by said arm.

Fig. XII is an elevation of the detent controlled by the release arm of the transmission shaft locking mechanism.

Fig. XIII is an elevation of the presser levers operable by the key levers and parts coöperable therewith, the parts operable by 70 one key lever being shown in normal positions and the parts operable by an adjoining key lever being shown in positions assumed when the last mentioned lever is depressed.

Fig. XIV is a perspective view of the collection of members by which the latch dog is released from the locking dog of the transmission shaft locking mechanism.

My calculating machine being one intended, more particularly, to be placed in 80 operation through the medium of the numeral key levers of a typewriting machine I will, without limiting myself to any particular means for rendering it operative, describe the machine as operated by the numeral key levers of any ordinary typewriting machine, as contemplated in my U. S. Patent No. 923,600, issued September 7, 1909. With this understanding I will first state that A designates the numeral key levers of a typewriting machine which is intended to be placed above my calculating machine, these key levers being provided with keys B and being of denominations from one to nine.

1 designates the base of my calculating machine surmounted by side members 2, which, with said base, form the frame of my machine. The frame thus formed preferably has attached to it a top housing 3 by 10 which an inclosure for the calculating mechanism is completed.

4 designates a transverse rod surmounted in the side frame members 2, 5 are integer wheels loosely arranged on said rod, there 10 being nine of these wheels responding to the

numeral key levers A. The integer wheels 5 are provided with peripheral teeth that are adapted to be placed in mesh with wheels on a constantly rotating shaft, whereby said 5 wheels will have partial rotation imparted to them in different degrees, each integer wheel being rotated a distance that causes it to impart to the transmission shaft a movement that is the equivalent of a series 10 of steps corresponding in number to the numerical value of the integer wheels.

6 designates the drive shaft and 7 the wheels fixed thereto to which the peripheral teeth of the integer wheels are moved in 15 order that the integer wheels may be partially rotated during engagement between their peripheral teeth and the drive wheels. 9 is a transmission shaft parallel with the integer wheel supporting rod 4 and the drive 20 shaft 6 and on which are rigidly mounted a series of transmission wheels 8. In the present machine all of the transmission wheels 8 except those operable by the "1" and "2" integer wheels are operable by 25 the peripheral teeth on the integer wheels to a degree corresponding to that to which said integer wheels are operated by the wheels on the drive shaft 6. The operation 30 of the transmission shaft by the integer wheels is in conformity to the degree of operation of each integer wheel during engagement of its peripheral teeth. The "1" and "2" integer wheels are caused to operate the transmission shaft in a manner similar 35 to the operation of this member by the other integer wheels but they coöperate with ratchet wheels, to be hereinafter referred to, instead of with transmission wheels 8.

The transmission shaft 9 is provided at 40 one of its ends with a miter wheel 10 that meshes with a miter wheel 11 on a transmission shaft 12 leading to registering mechanism (not shown). The parts just described are quite similar, in general, to corresponding 45 parts in my patent before mentioned, and reference may be had to said patent for a more complete understanding of the operation of said parts, and of a suitable connection between the registering mechanism and 50 transmission shaft operable by the integer wheels.

13 designates a transverse rod supported in front of the series of integer wheels 5, this rod serving as a support for certain 55 parts including a frame comprising side arms 14 pivoted to said rod, a rod 15 connecting the ends of the arms, and a rod 16 mounted in the arms 14 between the rods 13 and 15. The frame comprising the members 60 just mentioned is normally held in lowered position by one or more springs 17, see Figs. I and II, connecting said frame to the base or other stationary part of the machine.

18 designates dogs loosely mounted on the 65 transverse rod 13, the number of these dogs

being equal to the number of the integer wheels, the dogs being provided with rearwardly extending arms 19, having lateral lips 20, which lie in the path of travel of stop pins 5', projecting from the sides of the 70 integer wheels, the engagement of said parts providing for the integer wheels being normally held from rotation. The dogs 18 are provided with forwardly extending tail arms 21, which lie beneath the transverse 75 rod 15 carried by the arms 14, pivoted to the rod 13. The function of these tail arms will be hereinafter set forth. 23 are gravitational detents, loosely arranged on the rod 13 alongside the dogs 18, each detent being normally upheld by the rear arms of said dogs, due to engagement of lips 24 on the detents with the lips 20 of the dogs, so that while the stop pins of the integer wheels are normally in abutment against the arms of the 85 dogs the rear ends of said gravitational detents lie above said stop pins, but when the rear arms of the dogs are lowered to permit passage of the stop pins over the lips of said arms, the stop pins ride beneath the gravitational 90 detents, after which the latter move downwardly and occupy positions that will cause the next succeeding stop pins on the integer wheels to come into engagement with the detents, pending the return of the dogs 95 18 to their normal positions.

The means utilized in the present machine for imparting initial partial rotation to the integer wheels 5 may be advantageously set forth at this point in the description. 25 100 105 110 115 120 125 tation of the integer wheel to cause a peripheral tooth thereon to be brought into engagement with a wheel 7 on the drive shaft 6, following which the integer wheel 5 is operated by said shaft to a degree corresponding to the integer represented by the integer wheel. Such movement is communicated from the integer wheel to the transmission shaft 9 and therefrom to the registering mechanism of the machine.

A feature in the integer wheels of my present machine may best be described at this time. I have discovered that when the initially operative peripheral teeth of the 15 integer wheels are made rigid members of the integer wheels, it frequently happens that these teeth, failing to come into proper mesh with the teeth of the wheels they are moved to, become injured or broken owing 20 to improper engagement. To overcome this, I include in my integer wheels as foremost members of the groups of peripheral teeth thereon, spring controlled teeth 31 which are capable of yielding toward the axes of the 25 integer wheels. These teeth are pivoted to the integer wheels and each tooth is normally held in an outstanding position by a spring 31^a, see Fig. VIII, which permits inward movement of the tooth when pressure 30 is exerted thereagainst. It will be understood that when the points of the teeth 31 are brought into engagement with the points of the teeth of either the wheels 7 or 8, the teeth 31 will yield backwardly until they 35 pass over the points of the teeth they have become engaged with and ride readily into their proper positions, to thereafter move in harmony without any clash or interference in the initial engagement between the 40 teeth of the co-operating wheels.

The mechanism for operating the dogs 18 that control the rotation of the integer wheels 5 will next be described. This mechanism is operable by the numeral key levers 45 A and comprises a series of presser levers 32 located beneath said key levers and loosely mounted upon a pivot rod 33. The levers 32 include long longitudinal arms extending rearwardly from the pivot rod 33 and upon 50 the rear ends of these horizontal arms are sleeves 35 in which uprights 36 that receive the engagement of the key levers A are fitted. In view of the key bars A being arranged in different elevations in different 55 makes of typewriting machines, the numeral key levers of which may be used to operate the levers 32 I provide for vertical adjustment of the uprights 36, this vertical adjustment being obtained by furnishing the 60 uprights with teeth 37 which are engaged by pawls, pivoted to the sleeves 35, as shown in Fig. IV. Each presser lever 32 is provided with a rearwardly extending lower arm 34.

65 39 designates pull levers loosely mounted

upon a transverse pivot rod 40 located at the rear of the transverse pivot rod 33, these pull levers being provided with arms extending backwardly from their axes and the ends of which are seated immediately beneath the horizontal arms of the presser levers 32, the pull levers being normally held in contact with the presser levers 32 by springs 41. Each pull lever 39 has connected to it a pull rod 42 which extends rearwardly from the pull lever and is attached to an arm 22 forming a part of the dog 18 that is operable by said lever upon the depression of the numeral key lever A corresponding thereto. Upon the depression of a numeral key lever A the presser lever 39 operable thereby, is depressed, causing the pull lever 39 to be operated and the dog 18 to be so moved as to free the integer wheel corresponding thereto in order that said integer wheel may be operated in the manner previously explained.

Means is provided in the present machine for preventing the operation of the remainder of the presser levers 32 when one of them has been operated and until said lever has returned to its normal position. This means comprises a pair of rocker arms 43 mounted on a transverse pivot rod 40 adjacent its ends in which are mounted an upper connecting rod 44 and a lower stop rod 45. When any pull lever 39 is operated it acts against the stop rod 45 and moves it forwardly from the position shown in Fig. II to the position shown in Fig. XIII, during which movement the rearwardly extending lower arm 34 of the operated presser lever 32 moves forwardly in front of the stop rod 45, and said stop rod becomes positioned, as seen in Fig. XIII, in front of the 105 arms 34 of the unoperated presser levers 32, thereby preventing movement of the last mentioned levers until the presser lever 32 which has been operated has returned to its normal position under the influence of the 110 retracting spring 46 attached thereto.

I will next proceed to the description of the automatic locking mechanism for controlling the movement of the transmission shaft 9. 47 designates a controller wheel 115 fixed to the transmission shaft 9. This wheel, as illustrated in the drawings, is supplied with peripheral teeth which need not be herein considered, inasmuch as they are foreign to the present invention. Projecting from one of the side faces of the controller wheel are spaced lugs 48 arranged in a circular series. 49 is a locking dog pivoted at 51 to a post 52 located alongside of the controller wheel. The locking dog 49 is 125 located adjacent to the path of movement of the lugs 48 on the controller wheel and is provided with a tooth 50 which normally rests between two adjoining lugs 48, as seen in Fig. IX. A spring 58 serves to hold the 130

tooth of the dog between lugs of the controller wheel and to return the dog to its normal position, after it has been disengaged from the wheel in a manner to be subsequently explained.

5 55 designates a tappet pivoted at 56, intermediate its ends, to the post 52 and located immediately above the locking dog 49. This tappet is provided with a tooth 57 which normally engages a tooth 54 on the locking dog 49 and is operable by pressure thereagainst to move the rear end of the locking dog downwardly when the tappet 55 is freed from holding means to be described. The tappet 55 is operable by a spring 58, see Fig. IX. An upwardly extending arm 55' of the tappet normally lies in engagement with a rotatable detent 59, this detent being partially cut away so that 10 when it is partially rotated the tappet 55 is released. The rotatable detent 59 is fixed to a short shaft 60 extending through the post 52, and fixed to the opposite end of said shaft is a latch bolt barrel 61 in which is located a latch bolt 62 that is normally projected from the periphery of the barrel by a spring 63, see Fig. XI. The post 52 has at its side at which the latch bolt barrel 61 is located, an extension 52' provided with a 15 vertical channel 52^a into which the latch bolt barrel is made to fit by cutting out a curved portion of the adjacent wall of the extension, as seen at 52^b. This provision is made in order that the latch bolt 62 may 20 engage a member operable in the channel 52^a as about to be explained. The latch bolt barrel 61 and the rotatable detent 59 on the same shaft 60 are retained in their normal 25 positions by a spring 64 connecting said detent to the post 52.

20 65 designates a release bar of L-shape utilized to impart partial rotation to the shaft 60 for the purpose of disengaging the detent 59 from the tappet 55. This release bar is pivoted to the transverse rod 15 and has an 25 arm movable vertically in the channel 52^a in the post extension 52'. The said arm is provided near its lower end with a notch 66 adapted to receive the latch bolt 62, as 30 seen in full lines in Fig. XI and dotted lines Fig. XII. When any dog 18 is operated the tail arm 21 of said dog being located beneath the transverse rod 15, acts to elevate said rod and the frame of which it is a part, 35 whereby the release bar 63 is elevated. Upon this movement taking place the latch bolt 62 resting in the notch 66 in the release bar is moved upwardly in an arcuate path, whereby the barrel 61, the shaft 60, and the 40 detent 59 are rotated to a sufficient degree to permit escape of the upper arm 55' of the tappet 55 from said detent, and subsequent actuation of the latch dog 49 by said tappet. The rearwardly extending arm of the tappet 45 55 is provided with an antifriction roller 67

cooperable with the teeth of a ratchet wheel 68 fixed to the transmission shaft 9, this arrangement providing for the ratchet wheel imparting movement to the tappet, after the tappet has been released, in order that the 70 tappet may be restored to its normal position (shown in Fig. IX) where it will not interfere with the return of the locking dog 49 to normal position at the proper moment.

The release bar 65 moves upwardly to a 75 position where its notch 66 will lie above the latch bolt 62, and the latch bolt is then forced toward the axis of the barrel 61, the latch spring 63 being compressed at this time. After the tappet 55 has been released from the detent 59, the release bar 65 continues its upward movement to release the latch bolt 62 from the walls of notch 66. The spring 64 finally returns the detent 59 to its normal position (Fig. IX) when the 80 ratchet 68 is actuated to restore the tappet 55.

When the locking dog is operated by the tappet 55, to withdraw its tooth 50 from engagement with the controller wheel, a stud 71 thereon is lowered into engagement with a hooked latch arm 69 carried by a suitably mounted pivot rod 70 (see Fig. IX). The pivot rod 70 carrying the latch dog 69 also has fixed to it a trip arm 72 which extends 90 upwardly and forwardly, the said trip arm being provided with a cam face 73 and having connected to it a pull spring 74 which tends to move the parts 69 and 72 in a forward direction.

The latch device comprising the latch arm 69 is released from the locking dog 49 by mechanism about to be described. 75 is a transverse shaft mounted in suitable bearings 76 on the base of the machine, this shaft having fixed to it at its ends, rearwardly extending arms 77 and 78, the arm 78 being located in front of the trip arm 72 and being provided with a finger 79 which engages the cam 73 of said trip arm. The arms 77 and 78 are connected by a pivot rod 80 which extends transversely of the entire series of cam levers 25 by which initial movement is imparted to the integer wheels 5. This shaft 80 has loosely mounted thereon a series of double armed lifting levers 81, the rear arms of said levers resting normally upon tails 25' extending forwardly from the arms 30 of the cam levers 25 and the forward arms of said levers 81 rest upon the pivot rod 75, the last mentioned arms having ranged therein adjusting screws 82 by which the lift levers may be adjusted to properly seat the rear arms of the lift levers against the tails of the dogs 25. Upon the return movement of any cam lever 25 which had been placed in operation during the use of my machine the tail 25' carried by said cam lever acts against the rear arm of the lifting lever 81 directly above said tail, 130

and, as a consequence the shaft 80 and the arms 77 and 78, are elevated. When this action takes place the finger 79 carried by the arm 78 acts against the cam 73 on the trip arm 72 to move the trip arm and the latch dog 69 associated therewith in a rearwardly direction whereby the stud 71 on the locking dog 49 is permitted to escape from said latch dog in order that the locking dog 49 may return into engagement with the controller wheel 47 to lock it. For clearness of understanding of the operation of the automatic locking mechanism I will enumerate the operation of the different parts of this mechanism in sequence as follows. Upon the upward movement of the release bar 65 during upward movement of one of the dogs 18, and coincident operation of the corresponding cam lever 25, the rotatable detent 59 is partially rotated owing to the action of the released bar upon the latch bolt 62. The partial rotation of the detent permits operation of the tappet 55 by the spring 58, said spring being stronger than spring 53, and said tappet acts to so move the locking dog 49 that its tooth 50 is withdrawn from a position between two of the lugs 48 on the controller wheel and the stud 71 on said locking dog is lowered sufficiently to become caught beneath the hook of the latch arm 69. These operations take place previous to the engagement of the released integer wheel 5 and the corresponding wheel 8 on the transmission shaft 9, and, as a result, when coöperation of these parts takes place the controller wheel 47 is free to rotate instead of being held by the locking dog 49. Previous to the completion of the desired movement of the transmission shaft 9 a pin 5' on the integer wheel that is in operation rides into contact with the top edge of the cam lever 25 which has been brought into service and moves toward the apex 28 of said cam lever. As said pin approaches the apex of the cam lever it acts to depress the rear end of said lever and the tail 25' at the forward end of the cam lever is moved upwardly so that it acts against the rear arm of the lifting lever 81 therefore and the shaft 80 and the arms 77 and 78 to be elevated. As these upward movements take place the finger 79 extending rearwardly from the arm 78 rides in engagement with the cam 73 of the trip arm 72 and the latch dog 69 is thrown rearwardly to release the locking dog 49. The locking dog 49 being thus freed is actuated by the spring 53 to replace its tooth 50 between two of the lugs 48. While the locking dog is returning to its normal position the pin 5' that is acting to depress the cam lever 25 moves downwardly from the apex 28 along the inclined cam face 27 of the cam lever and is brought to rest back of said cam face so that it will be in position

for the next subsequent initial operation of the integer wheel in the manner first explained with respect to the placing of the integer wheels in coöperation with the driving wheels on the drive shaft 6. 70

The "1" integer wheel 5 and the "2" integer wheel 5 in this machine do not, as previously mentioned, operate the transmission shaft 9 by the engagement of their peripheral teeth with wheels 8 on said transmission shaft but, instead, their side pins engage ratchet wheels on said transmission shaft. The ratchet wheel 68 is engaged by the side pins of the "1" integer wheel, arranged singly and the side pins of the "2" integer wheel arranged in groups of two, see Fig. III, engage a ratchet wheel 83, see Fig. III, fixed to the transmission shaft 9, said ratchet wheel in combination with the spring controlled pawl 84 serving also to prevent retrograde rotation of said transmission shaft. 75 80 85

It is well to here recite that the integer wheels 5, aside from the "1" and "2" integer wheels, have either different numbers of groups of peripheral teeth or the groups spaced differently on the wheels; also that the teeth in each group correspond in number to the numerical value of the integer represented by the wheel, less one, to give 90 the desired movement, to the transmission shaft 9 following the initial step movement. It is further to be noted that the side pins 5' on said wheels correspond in number to the number of groups of teeth and are 100 spaced differently so that each pin will be accurately brought into position of rest back of the cam face 27 of the cam lever 25 at the completion of movement of the integer wheel in operation of the transmission shaft 9. It 105 should also be borne in mind that the operation of each integer wheel is independent of all other integer wheels and therefore the locations of the peripheral teeth and pins of said wheel does not in any way affect the 110 operations of any integer wheel other than the one in operation.

Furthermore the cam levers 25 have noses of different shapes so that they will readily enter between the pins 5', even though said pins are close to each other as they necessarily are on the wheels of the smaller integers which bear a greater number of groups of peripheral teeth than the wheels of large integers. In this connection attention is directed to Figs. 5 and 6 of my earlier Patent No. 933,600, herein mentioned, the similar cams 53 being different as will be readily perceived. 115 120

To afford a clear understanding of the operation with respect to a given integer, I will set forth the operation that takes place when the integer wheel shown in Fig. II is in service, this being the "6" integer wheel. The cam lever 25 here shown is similar to 125 130

all the other cam levers 25, except as to contour to permit entrance between the pins 5', and is constantly subject to the pull of the spring 29 connecting it to the frame of the machine. This being understood it will also be understood that when the "6" integer wheel is released from the holding influence of the dog 18, in front of a stop pin 5' on said wheel, the spring 29 will act to move the cam lever 25. This movement of said cam lever causes the cam face 27 at the rear end of the lever to ride in contact with a stop pin 5' during upward movement of the rear end of the lever, whereby an initial one step partial rotation is imparted to the integer wheel. This one step partial rotation of said wheel is sufficient to carry the first tooth of the group of peripheral teeth on the integer wheel, adjacent the alined driving wheel 7, upwardly into engagement with a tooth of said driving wheel. Said driving wheel is in constant rotation and immediately acts to drive the integer wheel during engagement of the teeth in the group with the teeth of the driving wheel, the distance of six steps, and consequently, the transmission wheel 8 operated by said wheel is also moved a distance of six steps. In this connection the statement should be made that the first tooth in a group on the integer wheel acts to drive the transmission wheel two steps before it will clear the transmission wheel and each succeeding tooth drives it one step. The movement of the "6" integer wheel is, naturally, discontinued when the last tooth of the group in service has become separated from the driving wheel 7 but this separation does not occur until a stop pin 5' on the integer wheel has reached the position of rest, seen in Fig. II, back of the cam face 27 ready to be impelled by the cam lever 25 upon the next release of the integer wheel in again placing the integer wheel and driving wheel in coöperation.

Each partial rotation of the "6" integer wheel by the cam lever 25 and driving wheel, in turn, is sufficient to carry the stop pin 5' on the integer wheel next to the one previously engaged by a dog 18 into engagement with said dog, and said dog becomes serviceable to restrain said wheel from actuation by the cam lever 25, pending movement of the dog, due to actuation of a corresponding key lever.

To afford a full understanding of the operation with respect to the "1" and "2" integer wheels it should be stated that the number of teeth on the ratchet wheels 68 and 83 correspond to the number of teeth on each transmission wheel 8. During a partial rotation of the "1" integer wheel by the corresponding cam lever 25 and driving wheel 7, in the same manner as described with respect to the "6" integer wheel, a stop pin 5' on said "1" integer wheel is caused to engage

a tooth of the ratchet wheel 68 and move said wheel and the transmission shaft 9 the distance of one step. Similarly, in the operation of the "2" integer wheel one of a pair of the twin stop pins 5' on said wheel first engages a tooth of the ratchet wheel 83 and moves it one step and the second pin immediately thereafter engages the same tooth and moves the ratchet wheel an additional step, thus giving the desired two step movement.

When my calculating machine is used as an adjunct to a typewriting machine, it is desirable to, at times, render the calculating mechanism inoperative by the numeral key levers of the typewriting machine, *i. e.* when there is no demand for the use of the calculating machine. To render the calculating machine inoperative at such a time I provide means whereby the presser levers 32 and their uprights 36 are withdrawn from positions where they will be operable by the numeral key levers of the typewriting machine and which I will now describe. The pivot rod 33 supporting the presser levers 32 is rockably supported by a frame comprising said pivot rod and upright rocker bars 85 in the upper ends of which said pivot rod is mounted. The rocker bars just mentioned are fixed to a transverse pivot rod 86 and when the presser levers 32 are in position to be operated by the key levers A, the rocker bars 85 are held upright by a spring 87, see Fig. II. 88 is a disconnect key the stem of which is vertically positioned in the main frame of the machine in front of the parts just described. The stem of this key is pivoted at 89 to the forward arm of a bell crank lever 90 which is supported by a transverse pivot rod 93. The bell crank lever 90 has a downwardly extending arm 94 which is pivoted to a lever 95 rockable upon a fulcrum 96 and connected by a link 97 to one of the rocker bars 85. When the disconnect key 88 is depressed it acts to operate the bell crank lever 90 whereby the latter acts upon the lever 95 and by throwing it rearwardly imparts movement to the connecting link 97, and the upper ends of said rocker bars are thrown forwardly, carrying with them the pivot rod 33, the result being that the presser levers 32 are moved forwardly and downwardly so that the uprights 36 carried thereby are withdrawn from positions that permit of their being engaged and operated by the numeral key levers A. The forwardly extending arm of the bell crank 90 operable by the disconnect key 88 has an inclined cam 91 at its lower edge that faces downwardly as seen in Fig. II, and extending backwardly in said cam is a notch 92. The provision of the cam and notch upon and in the bell crank lever 90 is made for the reception of a detent device by which the

bell crank lever 90 is held from movement after the disconnect key has been depressed with the object in view of holding the presser levers 32 in their forwardly adjusted and inoperative positions. The said detent device comprises latch arms 98 fixed to a transverse pivot rod 99 in which is mounted a transverse catch rod 100 (see Figs. I and II). The catch rod normally rests against the inclined cam 91 of the bell crank lever 90 and is held thereto by a spring 101. When the disconnect key is depressed the bell crank lever 90 is first operated in the manner described to effect retraction of the presser levers 32 and following such retraction the catch rod 100 enters into the notch 92 of the bell crank lever whereby the latter is locked from movement with the obvious result of maintaining the presser levers 32 in their retracted positions. Mounted on the rod 93 is a release key lever 103, having a key 102. Upon operation of the release key lever, which overlies the catch rod 100, said rod is thrown forwardly and downwardly so that the bell crank lever 90 is released from the holding influence of the catch rod 98. The springs 87 then act to return the rocker bars 85 and the parts associated with said bars to their normal positions, whereby the presser levers 32 are again adjusted into their operative positions.

I claim:

1. In a calculating machine, an integer wheel, means for operating said integer wheel, a transmission shaft operable by said integer wheel, a stop for said transmission shaft, key controlled devices including means for releasing said stop, and means providing for the return of said stop to its operative position at the completion of an operation of said integer wheel.
2. In a calculating machine, an integer wheel, means for operating said integer wheel, a transmission shaft operable by said integer wheel, a stop for said transmission shaft, key controlled devices including means for releasing said stop, and means controlled by said integer wheel providing for the return of said stop to its operative position at the completion of an operation of said integer wheel.
3. In a calculating machine, a series of integer wheels, means for operating said integer wheels, means for moving said integer wheels into coöperative relation with said operating means, a transmission shaft operable by said integer wheels, a locking device for stopping said transmission shaft, key controlled devices including means for releasing said locking device, and means controlled by said first mentioned integer wheel moving means providing for restoration of said locking device.
4. In a calculating machine, a series of integer wheels, means for operating said in-

teger wheels, cam levers for moving said integer wheels into coöperative relation with said operating means, a transmission shaft operable by said integer wheels, a locking device for stopping said transmission shaft, key controlled devices including means for releasing said locking device, and means controlled by said cam levers providing for restoration of said locking device.

5. In a calculating machine, a series of integer wheels, means for operating said integer wheels, a transmission shaft operable by said integer wheels, a stop for said transmission shaft, key controlled devices including means for releasing said stop, a spring tending to restore said stop, a latch for holding said stop during the operation of said transmission shaft, and a latch releasing member operable by said integer wheels at the completion of the operation of said wheels.

6. In a calculating machine, a series of integer wheels, a transmission shaft operable by said integer wheels, a stop wheel coöperable with said transmission shaft, a stop movable into engagement with said stop wheel, key controlled members for releasing said stop from said stop wheel, and means, controlled by said integer wheels, providing for the return of said stop to said stop wheel when an operation of the transmission shaft is completed.

7. In a calculating machine, a series of integer wheels, a transmission shaft operable by said integer wheels, a stop wheel coöperable with said transmission shaft, a stop movable into engagement with said stop wheel, key controlled mechanism for releasing said stop from said stop wheel, a stop holding device, and a stop releasing device including a series of members coöperable with said integer wheels.

8. In a calculating machine, a series of integer wheels, a transmission shaft operable by said integer wheels, a stop wheel coöperable with said transmission shaft, a stop movable into engagement with said stop wheel, key controlled mechanism for releasing said stop from said stop wheel, a stop holding device, and a stop releasing device including a series of independently adjustable members coöperable with said integer wheels.

9. In a calculating machine, a series of integer wheels, a transmission shaft operable by said integer wheels, a stop wheel coöperable with said transmission shaft, a stop movable into engagement with said stop wheel, means for disengaging said stop from said stop wheel, key controlled mechanism for releasing said disengaging means, a spring tending to move said stop into engagement with said stop wheel, a latch for holding said stop, and a latch releasing device operable by said integer wheels.

10. In a calculating machine, a series of integer wheels, a transmission shaft operable by said integer wheels, a stop wheel co-operable with said transmission shaft, a stop 5 movable into engagement with said stop wheel, spring actuated means tending to disengage said stop from said stop wheel, key controlled mechanism for releasing said spring actuated means, a spring tending to move said stop into engagement with said stop wheel, a latch for holding said stop, and a latch releasing device operable by said integer wheels. 10
11. In a calculating machine, a series of integer wheels, a transmission shaft operable by said integer wheels, a stop wheel co-operable with said transmission shaft, a stop movable into engagement with said stop wheel, means for disengaging said stop 15 from said stop wheel, key controlled mechanism for releasing said disengaging means, a spring tending to move said stop into engagement with said stop wheel, a latch for holding said stop, and a latch releasing device 20 operable by said integer wheels; the said latch releasing device comprising a plurality of fingers, and finger operating means operable by said integer wheels. 25
12. In a calculating machine, a series of integer wheels, a transmission shaft operable by said integer wheels, a stop wheel co-operable with said transmission shaft, a stop movable into engagement with said stop wheel, means for disengaging said stop from 30 said stop wheel, key controlled mechanism for releasing said disengaging means, a spring tending to move said stop into engagement with said stop wheel, and a latch releasing device operable by said integer 35 wheels; the said latch releasing device including a rockable member and a plurality of fingers associated therewith, and means operable by said integer wheels for operating said fingers. 40
13. In a calculating machine, a series of integer wheels, a transmission shaft operable by said integer wheels, a stop wheel co-operable with said transmission shaft, a stop movable into engagement with said stop wheel, a latch for holding said stop, a latch releasing device operable by said integer 45 wheels, the said latch releasing device comprising a rockable member having a series of independently adjustable fingers associated therewith, and means operable by said integer wheels for operating said fingers. 50
14. In a calculating machine, a series of integer wheels, a transmission shaft operable by said integer wheels, a stop wheel co-operable with said transmission shaft, a stop movable into engagement with said stop wheel, a spring actuated member tending to disengage said stop from said stop wheel, key controlled mechanism for releasing said 55
- spring actuated member, a spring tending to move said stop into engagement with said stop wheel, a latch for holding said stop, and a latch releasing device comprising a rockable member and a plurality of independently adjustable fingers associated therewith, and cam levers operable by said integer wheels for operating said fingers. 60
15. In a calculating machine, a series of integer wheels having peripheral teeth, a series of transmission wheels adapted to mesh with said rows of peripheral teeth, a shaft to which said transmission wheels are fixed, means for stopping said shaft after the integer wheels are disengaged from said transmission wheels, said means including a stop wheel operable by said transmission shaft, and a stop member adapted to interlock with said stop wheel, and key controlled devices for disengaging said stop member from said stop wheel. 65
16. In a calculating machine, a series of integer wheels having peripheral teeth, a series of transmission wheels adapted to mesh with said rows of peripheral teeth, a shaft to which said transmission wheels are fixed, means for stopping said shaft after the integer wheels are disengaged from said transmission wheels, said means including a stop wheel operable by said transmission shaft, a stop member adapted to interlock with said stop wheel, key controlled devices for disengaging said stop member from said stop wheel, and means controlled by said integer wheels for restoring said stop member. 70
17. In a calculating machine, an integer wheel, integer wheel operating means, key actuated means for controlling said integer wheel, a transmission shaft operable by said integer wheels, and locking mechanism for said transmission shaft co-operable with said means for controlling said integer wheel. 75
18. In a calculating machine, an integer wheel, integer wheel operating means, key actuated means for controlling said integer wheel, a transmission shaft operable by said integer wheel, and locking mechanism for said transmission shaft co-operable with said means for controlling said integer wheel; said locking mechanism being movable in response to movements of said integer wheel. 80
19. In a calculating machine, key operated members, a series of integer wheels, means for operating said integer wheels, cam levers for moving said integer wheels into co-operative relation with said operating means, a transmission shaft operable by said integer wheels, means for locking said transmission shaft after operation. 85

thereof by said integer wheels, and means under control of said key operated members whereby said locking means is released to permit the operation of said transmission shaft.

20. In a calculating machine, an integer wheel, integer wheel operating means, a transmission shaft, means for imparting an initial movement to said integer wheel to render it coöperative with said operating means and transmission shaft, key actuated means for controlling said integer wheel, and locking mechanism for said transmission shaft coöperable with said key actuated means and also coöperative with said means for imparting initial movement to said integer wheel.

21. In a calculating machine, an integer wheel, integer wheel operating means, a transmission shaft, a spring actuated member for moving said integer wheel into engagement with said operating means and said transmission shaft, key actuated means for controlling said integer wheel, and locking mechanism for said transmission shaft coöperable with said key actuated means.

22. A calculating machine comprising keys, and calculating mechanism operable in response to movements of said keys, said calculating mechanism including a stop wheel, a locking dog adapted to interlock with said stop wheel, means for releasing said locking dog upon the operation of a key, and means for automatically restoring said locking dog when a calculating operation is completed.

23. A calculating machine comprising keys and calculating mechanism operable in response to movements of said keys, said calculating mechanism including a stop wheel provided with a series of stop teeth, a locking dog adapted to interlock with said stop teeth, key controlled devices for withdrawing said locking dog from said stop teeth upon the operation of any of said keys, and restoring devices for automatically interlocking said locking dog with said stop wheel when a calculating operation is completed.

24. A calculating machine comprising keys, and calculating mechanism operable in response to movements of said keys; said calculating mechanism including a toothed stop wheel, a locking dog adapted to interlock with the teeth on said stop wheel, key controlled devices for disengaging said locking dog from said teeth, a latch for holding said locking dog during the operation of the calculating mechanism, and means for automatically operating said latch and restoring the locking dog when a calculating operation is completed.

25. A calculating machine comprising keys, and calculating mechanism operable in

response to movements of said keys, said calculating mechanism including a stop wheel, a locking dog adapted to interlock with said stop wheel, means for releasing said locking dog upon the operation of a key, a latch device for holding said locking dog during the operation of the calculating mechanism, means for releasing said latch device when a calculating operation is completed, and a spring for moving said locking dog into engagement with said stop wheel.

26. A calculating attachment for typewriting machines comprising calculating mechanism operable by the key levers of a typewriting machine, said calculating mechanism including adjustable members adapted to be engaged by the key levers of the typewriting machine.

27. A calculating attachment for typewriting machines comprising calculating mechanism operable by the key levers of a typewriting machine, said calculating mechanism including presser members provided with vertically adjustable extensions adapted to be engaged by the key levers of the typewriting machine.

28. In a calculating machine, an integer wheel, integer wheel operating means, key actuated means for controlling said integer wheel, a transmission shaft adjacent to said integer wheel, a ratchet wheel on said transmission shaft, said integer wheel being provided with means for engagement with said ratchet wheel to impart a step by step movement to said transmission shaft.

29. In a calculating machine, an integer wheel, integer wheel operating means, key actuated means for controlling said integer wheel, a transmission shaft adjacent to said integer wheel, a ratchet wheel on said transmission shaft, said wheel being provided with a pin for engagement with said ratchet wheel to impart partial rotation to said transmission shaft during only the period of engagement between said pin and said wheel.

30. In a calculating machine, an integer wheel, means for operating said integer wheel, a transmission shaft operable by said integer wheel, a stop for said transmission shaft, key controlled devices including means for releasing said stop, and means coöperable with said integer wheel providing for the return of said stop to its operative position at the completion of an operation of said integer wheel.

31. In a calculating machine, a series of integer wheels, means for operating said integer wheels, means for moving said integer wheels into coöperative relation with said operating means, a transmission shaft operable by said integer wheels, a locking device for stopping said transmission shaft, key controlled devices including means for

releasing said locking device, and means co-operable with said first mentioned integer wheel moving means providing for restoration of said locking device.

5 32. In a calculating machine, a series of integer wheels, means for operating said integer wheels, cam levers for moving said integer wheels into co-operative relation with said operating means, a transmission shaft 10 operable by said integer wheels, a locking device for stopping said transmission shaft, key controlled devices including means for releasing said locking device, and means co-operable with said cam levers providing for 15 restoration of said locking device.

33. In a calculating machine, a series of integer wheels, means for operating said integer wheels, a transmission shaft operable by said integer wheels, a stop for said transmission shaft, key controlled devices including means for releasing said stop, a spring tending to restore said stop, a latch for holding said stop during the operation of said transmission shaft, and a latch releasing 25 member co-operable with said integer wheels at the completion of the operation of said wheels.

34. In a calculating machine, a series of integer wheels, a transmission shaft operable by said integer wheels, a stop wheel co-operable with said transmission shaft, a stop movable into engagement with said stop wheel, key controlled members for releasing said stop from said stop wheel, and means, 30 co-operable with said integer wheels, providing for the return of said stop to said stop wheel when an operation of the transmission shaft is completed.

35. In a calculating machine, a series of integer wheels, a transmission shaft operable by said integer wheels, a stop wheel co-operable with said transmission shaft, a stop movable into engagement with said stop wheel, means for disengaging said stop from 40 said stop wheel, key controlled mechanism for releasing said disengaging means, a spring tending to move said stop into engagement with said stop wheel, a latch for holding said stop, and a latch releasing device co-operable with said integer wheels.

36. In a calculating machine, a series of integer wheels, a transmission shaft operable by said integer wheels, a stop wheel co-operable with said transmission shaft, a stop 55 movable into engagement with said stop wheel, spring actuated means tending to disengage said stop from said stop wheel, key controlled mechanism for releasing said spring actuated means, a spring tending to move said stop into engagement with said stop wheel, a latch for holding said stop, and a latch releasing device co-operable with said integer wheels.

37. In a calculating machine, a series of

integer wheels, a transmission shaft operable by said integer wheels, a stop wheel co-operable with said transmission shaft, a stop movable into engagement with said stop wheel, means for disengaging said stop from said stop wheel, key controlled mechanism 65 for releasing said disengaging means, a spring tending to move said stop into engagement with said stop wheel, a latch for holding said stop, and a latch releasing device operable by said integer wheels; the said latch releasing device comprising a plurality of fingers, and finger operating means co-operable with said integer wheels.

38. In a calculating machine, a series of integer wheels, a transmission shaft operable by said integer wheels, a stop wheel co-operable with said transmission shaft, a stop movable into engagement with said stop wheel, means for disengaging said stop from said stop wheel, key controlled mechanism 80 for releasing said disengaging means, a spring tending to move said stop into engagement with said stop wheel, and a latch releasing device operable by said integer wheels; the said latch releasing device including a rockable member and a plurality 85 of fingers associated therewith, and means co-operable with said integer wheels for operating said fingers.

39. In a calculating machine, a series of integer wheels, a transmission shaft operable by said integer wheels, a stop wheel co-operable with said transmission shaft, a stop movable into engagement with said stop wheel, a latch for holding said stop, a latch 95 releasing device operable by said integer wheels, the said latch releasing device comprising a rockable member having a series of independently adjustable fingers associated therewith, and means co-operative with 100 said integer wheels for operating said fingers.

40. In a calculating machine, a series of integer wheels, a transmission shaft operable by said integer wheels, a stop wheel co-operable with said transmission shaft, a stop movable into engagement with said stop wheel, a spring actuated member tending to disengage said stop from said stop wheel, key controlled mechanism for releasing said 110 spring actuated member, a spring tending to move said stop into engagement with said stop wheel, a latch for holding said stop, and a latch releasing device operable by said integer wheels; the said latch releasing device comprising a rockable member and a plurality 115 of independently adjustable fingers associated therewith, and cam levers co-operable with said integer wheels for operating said fingers.

41. In a calculating machine, a series of integer wheels having peripheral teeth, a series of transmission wheels, adapted to

mesh with said rows of peripheral teeth, a shaft to which said transmission wheels are fixed, means for stopping said shaft after the integer wheels are disengaged from said 5 transmission wheels, said means including a stop wheel operable by said transmission shaft, a stop member adapted to interlock with said stop wheel, key controlled devices

for disengaging said stop member from said stop wheels, and means coöperable with said 10 integer wheels for restoring said stop member.

FERDINAND J. TILLMAN.
